UNITED STATES PATENT OFFICE

99,826

DESIGN FOR A SERVICE STATION RESTAURANT

Theodore T. Record, Santa Barbara, Calif.

Application March 11, 1936, Serial No. 61,571

Term of patent 14 years

To all whom it may concern:

Be it known that I, Theodore T. Record, a citizen of the United States, residing at Santa Barbara, in the county of Santa Barbara and State of California, have invented a new, original, and ornamental Design for a Service Station Restaurant, of which the following is a specification, reference being had to the accompanying drawing, forming part thereof.

I claim:

The ornamental design for a service station restaurant, as shown.

T. T. RECORD.
